CLAIM

The ornamental design for a pet products package, as shown and described.

DESCRIPTION

FIG. 1 is a top plan view of a pet products package showing my new design, in an unfolded configuration;

FIG. 2 is a front, right, and top perspective view thereof in a folded configuration;

FIG. 3 is a rear, left and top perspective view thereof;

FIG. 4 is a front and right perspective view thereof;

FIG. 5 is a front view thereof;

FIG. 6 is a rear view thereof;

FIG. 7 is a top view thereof;

FIG. 8 is a bottom view thereof;

FIG. 9 is a right view thereof; and,

FIG. 10 is a left view thereof.

The broken lines in the drawing depict fold lines that form part of the claimed design.
